UNITED STATES PATENT OFFICE

162,146

SET OF BLOCKS

George W. French, Chicago, Ill.

Application November 6, 1948, Serial No. 149,500

Term of patent 7 years

(Cl. D34—15)

To all whom it may concern:

Be it known that I, George W. French, a citizen of the United States, residing at Chicago, in the county of Cook and State of Illinois, have invented a new, original, and ornamental Design for a Set of Blocks, of which the following is a specification, reference being had to the accompanying drawing, forming a part thereof.

In the drawing:

The drawing figure is a top plan view of a set of blocks, showing my new design, and has been shaded to show contrasting appearance. The blocks are substantially thin and flat.

I claim:

The ornamental design for a set of blocks, as shown and described.

GEORGE W. FRENCH.
